WASHING MACHINE

Jay Grant De Remer, Darien, Conn., assignor to
 J. G. De Remer Research Corporation, Union
 City, N. J., a corporation of New Jersey

Application March 18, 1939, Serial No. 262,652

23 Claims. (Cl. 68—23)

The invention relates to washing machines having centrifugal separating apparatus for drying and represents an improvement over Motycka Patent No. 2,137,540, dated November 22, 1938.

When a basket, supported by a universal joint under it, is rotated about a vertical axis at centrifugally discharging spinning speed, under certain conditions, it tends to precess, that is, the basket axis rotates about a true vertical axis through the universal joint, following a spiral path, swinging further and further away from the true vertical position. To overcome this action, according to the prior patent, an accelerating force is applied to the basket, tangential to its path of precession, to cause the rotating basket to move toward true vertical position so that the center of mass of the basket and its contents will lie directly in line with the central point of support. One form of washing and drying machine embodying the above principles may comprise a tank having a basket driven by a vertical spin shaft having a universal joint and journalled in the tank bottom.

According to the present invention, the gyrating motion may be applied to the basket by a sleeve surrounding the spin shaft and spaced therefrom to permit the precessing movement of the spin shaft. Suitable coaction may be provided between the gyrating shaft and the spin shaft for the washing and drying operations. In one form, a spherical plate or cup is journalled on the spin shaft and a ring having a spherical surface is secured to the gyrating shaft. These surfaces frictionally engage during the drying operation to provide the corrective force above referred to. For the washing operation, a socket in a ring on the gyrating shaft engages a hub journalled on the spin shaft, this hub being movable into said socket by elevation of the spin shaft.

Suitable driving connections may be provided for the spinning and gyrating shafts. The gyrating shaft may have a large friction gear secured thereto and the spinning shaft a somewhat smaller friction gear. A drive motor may be suspended from the tank bottom, having a friction gear on each end engaging the gyrating and spin shaft friction gears.

For shifting between washing and drying operations, a stationary brake element is moved up

and down by suitable devices. When the brake element is moved upwardly, it engages the spinner shaft friction gear, disengaging the spinner shaft gear from the motor gear and positively engaging the hub on the spinner shaft with the recess in the gyrating shaft ring. Thus, when the shifting element is in upper position, the spinner is prevented from rotating on its own axis, but is positively gyrated by the gyrating shaft.

The laundry machine, according to the invention, is particularly adapted for full automatic operation and, if desired, the shifting element may be operated by a suitable nut and screw mechanism driven by a small reversible control motor. Suitable contact and circuit devices may be provided for controlling hot and cold water and the control motor, whereby the clothes may be washed, rinsed and dried entirely automatically, each operation being timed without further attention from the operator after the clothes have been placed in the basket.

The invention also consists in certain new and original features of construction and combination of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 is a vertical elevation of the laundry machine with parts shown in section;

Fig. 2 is a vertical section through the main drive shaft assembly;

Fig. 3 is a diagram showing a completely automatic operation;

Fig. 4 is a section on the line 4—4 of Fig. 1;

Fig. 5 is a detail of the gyrating ring used for the washing operation; and

Fig. 6 is a diagram illustrating the operation of the vibration correction device.

In the following description and in the claims, various details will be identified by specific names for convenience, but they are intended to be as generic in their application as the art will permit.

Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

Referring now to the drawings and, more particularly, to Figs. 1 and 2, the laundry machine comprises, in general, an outer tank 10 enclosing an imperforate type of clothes basket 11. The basket 11 is supported by a drive shaft assembly, including a spin shaft 12 and gyrating sleeve 13. Main electric motor 14 drives both the spin shaft 12 and gyrating shaft 13, and control motor 15 automatically shifts the machine back and forth between washing and drying operations. Pump 16 is for the purpose of emptying the tank into a sink or the like.

The basket 11 is made of suitable material, such as sheet metal and comprises a dished bottom 20 running into an upwardly and outwardly flaring side wall 24. An annular ring 25 having apertures 26 is secured to side wall 24. Ring 25 has an inturned flange 27 for retaining the laundry during the washing and drying operations.

A plurality of baffles 28 are secured to the side wall 24 to assist in agitating the laundry during the washing operation. Two diametrically opposed baffles may be used, as shown, or any larger number. The basket 11 is supported by stub shaft 21 having a top plate 22. The bottom wall 20 of the spinner is secured between plate 22 and cooperating plate 23 by welding, brazing, or in any other suitable way.

Tank 10 is made up of a structural base ring 31 supporting an annular side wall 32 and in turn supported by legs 33, three legs being shown for purposes of illustration. The bottom of the tank is made up of an annular trough 34 secured to the sleeve or pedestal 35. An annular flared bracing member 36 is secured to sleeve 35 and to the bottom of trough 34, as indicated particularly in Fig. 1. The sheet metal members 32, 34, 35 and 36 may be secured together by welding or brazing, or in any other way well known in the art.

The cover for tank 10 comprises a flat ring 37 seated within the upper edge of the tank and having an annular seat 42. Seated on this seat is central lid 38 having a depending flared wall 39. Secured to the top of wall 39 is a flat wall 40. Walls 39 and 40 provide a chamber and acts as baffles to prevent water from being thrown out of the machine during the washing operation. At the same time, walls 39 and 40 have aligned openings for feeding wash water through supply hose 138.

The drive shaft assembly comprises sleeve 35 which journals sleeve shaft 13, which in turn journals spin shaft 12. The sleeve or pedestal 35 carries a lower shoulder ring 44 providing a radial bearing for gyrating shaft 13 and a collar 45 is secured to shaft 13 to provide a vertical thrust bearing operating against ring 44.

The spin shaft 12 comprises a lower section 50 and upper section 51 connected by a universal joint 52, permitting the upper section 51 to spin with the lower section 50 and also to execute a conical precessing movement about the center of universal joint 52, as will be explained more in detail hereinafter. Ring 53 is secured to gyrating sleeve 13 and supports bearing sleeve 54 75

for journaling lower section 50. Bearing washers 55 act between ring 53 and the shoulder on universal joint 52 to take the vertical thrust of spin shaft 12.

5 The upper section 51 has a sleeve 56 fixedly secured thereto, this sleeve being splined to receive a complementary splined end 57 of basket stub shaft 21. Spring 58 acts between a recess in upper section 51 and the bottom of stub shaft 10 21 for a purpose hereinafter described.

To overcome precession, the gyrating shaft 13 applies an accelerating force to the precessing basket shaft made up of shafts 51 and 21 above universal joint 52. To impart this accelerating force, friction rings 60 are secured to the upper edge of gyrating shaft 13. Friction rings 60 cooperate with a spherical cup or plate 61 which is secured to sleeve 62, which in turn supports bearing bushing 63 journalled on sleeve 56. The bushing 63 is flared at both ends for a purpose hereinafter described. The spherical friction surfaces on cup 61 and friction rings 60 are laid out about the center of universal joint 52 when in its lower or drying position, indicated in Fig. 2.

25 For transferring weight from the basket 11 to the spherical cup 61, a sleeve 64 is provided, journalled on cup 61 by bearing ring 65. A shield 66 is secured to cup 61 and carries a felt washer 67 bearing against ring 64 for the purpose of retaining lubricant within the shield 66 and for preventing water from getting into the bearing mechanism. Shield 68 is secured to gyrating sleeve 13 to prevent water getting into the drive shaft assembly.

30 35 In the position shown in Fig. 2, the parts are in their drying position and the drying operation has just begun. Spin shaft 12 rotates at a centrifugally extracting speed and at the same time gyrating shaft 13 rotates in the same direction at a slower speed. The friction members 60 and 61 carry the basket shaft 21, 51 journalled in bearing 63 in a conical path.

35 40 For washing, a gyrating ring 71 is secured to gyrating shaft 13. Ring 71, shown in detail in Fig. 5, has an off-center recess 72 adapted to receive a ring or bushing 73 tapered to seat easily within recess 72. Spin shaft 12 is raised in a manner hereinafter described to cause ring 73 to seat in recess 72. Ring 73 is journalled radially by bearing 76 and axially between collars 74 and 75 fixed on shaft 56.

45 50 For driving the machine, an electric motor 14 is bolted to saddle 79. Saddle 79 has side ears 77 pivoted at 81 to side walls 78 of hanger 80. Hanger 80 is suspended from pivot 82 secured to base ring 31.

55 60 The shaft of electric motor 14 carries bevel friction gears 83 and 84, engaging respectively gears 86 and 85 on lower section 50 and gyrating shaft 13. Spring 87 acts between the adjacent leg 33 and an ear 77 of saddle 79 to yieldably urge friction gears 83 and 84 into engagement with friction gears 86 and 85. A stop 89 is secured to a leg 33 and an adjustable screw 88 is secured to saddle 79 to limit the upward movement of gear 83 when it is disengaged from gear 86 for the purpose hereinafter described.

65 70 Referring to Fig. 2, the pump 16 comprises a casing 91 having an impeller 92 pinned to lower section 50. The casing 91 is journalled on shaft 50 and has inlet 93 and outlet 94. Flexible hose 95 connects inlet 93 with a drain tube 97 connected to the tank bottom (Fig. 1). Flexible hose 96 connects discharge outlet 94 with a gooseneck 98 adapted to be hung over the edge of a

sink, as will be understood by those skilled in the art. The water flows in the direction of the arrows and the flexible hose 95 resists the torque on casing 91 caused by the pumping action.

The position of the parts shown in Figs. 1 and 2 is the drying position at the beginning of the drying operation. To shift from drying position to washing position, the spin shaft 12 is elevated, this disengaging drive gears 83 and 86 and engaging gyrating bushing 73 with the recess in gyrating ring 71.

The shifting mechanism is as follows: A brake collar 100 engages gear 86 to elevate spin shaft 12, to disengage gears 83 and 86 and to stop the spin of shaft 12. The brake collar has trunnions 102 supported between arms 101. The raising and lowering of arms 101 is done by control motor 15 which is supported on plate 104 (Figs. 1 and 4).

Plate 104 is supported by the hangers 103 and by the adjacent leg 33 of the machine. Plate 104 also supports a worm gear reduction unit 112 made up of a worm 105 on the drive shaft of motor 15, which meshes worm wheel 106 on screw shaft 107. Screw shaft 107 engages nut 108 having trunnions 109 connected to the forked end of arm 100 which is secured to pivot shaft 111. Pivot shaft 111 is supported by hangers 113 from the bottom of plate 104 and carries the arms 101.

It will be apparent from Fig. 1 that when current is supplied to control motor 15, it will rotate screw shaft 107, causing nut 108 to move downwardly, which in turn imparts upward movement to brake collar 100 which shifts the machine from the drying to the washing position in the manner described above. Reversal of the control motor 15 will bring the parts back to the position shown in Fig. 1.

The above described machine is especially adaptable for full automatic operation. With such operation, it is only necessary for the operator to place the clothes in the basket and make certain settings and thereafter all washing, rinsing and drying is done entirely automatically, each operation being timed, and no further attention from the operator is necessary until it is time to remove the clothes from the basket for hanging out to dry or for ironing.

Referring now to Fig. 3, a circuit arrangement is shown for controlling the automatic operation. The arrangement comprises a dial having a clock shaft 116 which may be the minute shaft of any suitable clock mechanism, either electric or spring driven. Secured to minute shaft 116 is a contact arm 117 which may be secured to shaft 116 by any ordinary friction clutch commonly used in clocks, whereby the contact arm 117 may be rotated by the operator independent of the clock mechanism. Arranged in the path of the contact arm are sector rings 118, 119, and contacts 120-131.

The several sector rings and contacts are connected to a source of power 114 which may be any ordinary A. C. or D. C. household power line, which power is controlled by a switch 115. Connected in circuit is the main drive motor 14 of the machine and the control motor 15. Also connected in circuit is a solenoid operated water valve 135 connected in a hot water supply line H and a second solenoid operated water valve 136 connected in a cold water supply line C. Connected in the hot water line H is a soap box 137 in which may be placed soap chips or soap powder which is carried into the machine by the flow of hot water. Pipes H and C are connected to 75

hose 138 which passes through the cover of tank 10.

It will be understood that, if desired, the solenoid valves 135 and 136, soap container 137, 5 contact dial and control switch 115 may be suitably built into the machine.

Operation

The drying operation will first be described 10 since the machine is shown in position at the beginning of this operation. The nut 108 has just reached its uppermost position on screw shaft 107 and the brake ring 100 has just permitted friction gear 86 to engage motor friction gear 83 and has just released gear 86 from braking action. Gyrating shaft 13 is already moving at washing speed and spin shaft 12 is beginning to rotate at drying speed. In explaining this operation, it will be first assumed that the clothes 15 and everything spinning with the basket 11 are perfectly balanced with respect to the basket axis. In actual practice this condition will rarely or seldom occur and the basket will spin about a theoretical center of mass spaced from the geometrical basket axis, but the correcting action is 20 substantially the same in both cases.

The basket 11 partakes of two movements, (1) a spinning movement about its own axis, and (2) a gyrating movement about the center of universal joint 52, the basket axis describing a conical surface. Friction rings 60 carry friction cup 61 in a circular path, the basket shaft 21 spinning within cup 61 by means of bearings 63 and 65.

It will thus be seen that the gyro-stabilizer 25 including gyrating shaft 13 exerts a force on the basket 11 tangential to its conical precessional movement. The direction of rotation of gyrating shaft 13 is the same as the direction of spin 30 shaft 12 and gyrating shaft 13 impresses an accelerating force on the precessional movement of the basket. The tangential accelerating force causes the basket to move in a direction at right angles to the force or toward true vertical position, the friction surfaces 60 and 61 permitting the basket 11 to take a true central position in which the vertical axis of drive shaft section 50 coincides with the basket axis, assuming the clothes are evenly distributed and everything secured to and partaking of the same movement as the basket 11 is perfectly balanced about the basket axis.

In case the clothes are not evenly distributed, 35 the gyro-stabilizer will center the entire whirling mass about the theoretical center of mass which will differ slightly from the axis of the spinner basket and shaft 21. In this case, there will be a slight circular motion of the spherical cup or disc 61 on ring 60, but the correcting force acting toward true vertical due to the correcting 40 action of gyrating shaft 13 will nevertheless continue to exist.

After the basket 11 has been spun at centrifugally extracting speed a sufficient length of time 45 to expel the water from the clothes, the automatic control operates control motor 15 in such direction as to drive nut 108 downwardly on screw shaft 107. This causes brake ring 100 to engage spin gear 86, disengaging it from drive gear 83 and arresting the spinning movement of spin shaft 12. Further downward movement of nut 108 elevates spin shaft 12, raising the universal joint 52 off thrust bearing 55, compressing spring 58 and moving sleeve shaft 56 and gyrating ring 73 upwardly to engage in the socket 72.

of gyrating ring 11, the tapered surface of these members facilitating seating of these parts.

It will be noted that the basket 11 partakes of no upward movement, but that the basket shaft 21 telescopes down within sleeve shaft 56, compressing spring 58. Friction members 60 and 61 maintain contact, the flaring ends of bearing bushing 63 accommodating the upward shift of universal joint 52 which places it slightly off center with respect to the center of curvature of the spherical surface of friction members 60, 61.

This is the washing position. The gyrating shaft 13 carrying gyrating ring 11 positively moves ring 13 in a circular path, but the basket shaft 21 partakes of no rotation about its own axis because spring 58 provides sufficient contact pressure between gear 86 and brake ring 100 to hold these members in non-slipping relation during washing.

Thus the basket 11 with its measured contents of water and clothes is gyrated about the center of universal joint 82 in elevated position, the agitator blades 28 helping to tumble the clothes, opening them up and exposing all parts to the washing action of the water. The ring 25 and flange 27 on the basket prevent the water from sloshing out during washing, the baffles 39 and 40 on the tank cover directing any water which might spout upwardly back into the basket and preventing this water from discharging out of the machine.

After the clothes are washed for a sufficient length of time, the control motor 15 drives the nut 108 upwardly to the position shown in Fig. 1, this movement disengaging gyrating rings 11 and 13, engaging the universal joint 52 with thrust bearing 55, engaging spin gear 86 with motor gear 83 and disengaging the brake ring 100 from the spin gear 86. The frictional surfaces of gears 83 and 86 permit the necessary slipping to drive spin shaft 12 up to centrifugally discharging speed. Here again spring 58 helps supply the necessary downward pressure to spin gear 86. Most of the weight of basket 11 and contents during drying is borne by spherical friction members 60 and 61.

The automatic control functions as follows: Assume the contact arm 117 is resting off all contacts in position X from a previous run and the switch 115 is open. The machine is in the washing position. The clothes will be placed in the basket and the soap container 137 will be filled. It is only necessary then to close power switch 115 and to start the clock driving minute shaft 116.

Engagement of arm 117 with contact button 120 operates cold water solenoid 136 to deliver a measured amount of cold water into basket 11. The moving arm 117 contacts sector rings 118, 119, thereby starting the one-quarter horse power main driving motor 14. The machine being in the washing position, the clothes are then given a pre-rinse in cold water of, say, five minutes until the contact arm 117 hits button 121. This causes control motor 15 to shift the brake ring 100 to the drying position. The machine now spins the water out of the clothes for, say, five minutes until arm 117 reaches buttons 122, 123.

It will be understood that the time that arm 117 remains in contact with any of the buttons 120-131 depends upon the width of the buttons, with any given width of arm. The widths of the various buttons may, therefore, be selected to allot the proper times to carry out the functions controlled by the widths of these contacts.

For example, contact button 120, operating cold water solenoid 136, may cause cold water to flow for one and one-half minutes, assuming the water supply is adjusted to four gallons per minute and the capacity of the basket is six gallons. The width of button 121 may be selected to operate control motor 15 just a little longer than is necessary to drive nut 108 from its lower to its upper position.

Upon contacting button 122, the control motor 15 will be reversed, thereby returning the machine to washing position. At the same time, contact with button 123 opens hot water valve 135, causing hot water to pass through the soap box 137 and fill the basket with a predetermined amount of hot water and soap. The machine will now wash for a predetermined time, say, ten to twenty minutes, until contact arm 117 engages button 124 which again shifts the machine to the drying position.

The machine will dry for a predetermined time, say, five minutes, until contact arm 117 contacts button 126 which causes the machine to shift to washing position. Contact with button 125 opens hot water valve 135 to give the clothes a hot rinse.

The hot rinsing will take place for, say, five minutes, until contact arm 117 touches button 127 which shifts the machine to drying position, after which the machine may dry for, say, five minutes. The drying operation continues until contact arm 117 touches button 129 which shifts the machine to washing position. Contact with button 128 again opens hot water valve 135 which fills the basket with hot water for a second hot rinse.

This hot rinse may continue for, say, five minutes, until contact arm 117 hits button 130 which shifts the machine to the drying position. This drying operation will continue for, say, ten or fifteen minutes, if it is desired to spin the clothes dry enough for ironing, or until contact arm 117 engages button 131 which shifts the machine to washing position, or ready for the next batch of clothes. As the arm 117 passes off of sector rings 118, 119 to position X, main drive motor 14 stops and, if desired, the clockwork may also have been set to stop automatically.

The machine is now at rest and in the starting position. The clothes have been spun dry and may be removed from the machine by the operator. The new batch of clothes may be placed in the basket; the soap box 137 filled again, and the automatic control set to operate upon this batch of laundry in the same manner as above described.

Comments and advantages

I have found that the corrective or gyrating speed of shaft 13 must lie between certain limits with any given set of conditions for proper corrective action to take place. The behavior of a spinning basket supported by a universal joint under the center of mass of the basket obeys Equation #1 set forth below.

In the explanation of the various quantities below, the term "spinning mass" means the basket and everything attached thereto and partaking of a spinning and gyrating movement, including the shafts 21 and 51. If the basket is loaded with clothes, the load is also included.

The operation will be better understood by referring to Fig. 6 in which the same reference characters indicate the same parts as in the other figures. The true vertical axis passing through

the center of shaft section 50 is denoted by 150; the geometrical axis of basket 11 is denoted by 151; the clothes by 152 and the effective diameter of a flywheel gyroscopically equivalent to the entire spinning mass is denoted by 153.

The Equation #1 is as follows:

$$(1) \quad A \cos \alpha \Omega^2 - C \omega \Omega + mgh = 0$$

Where, referring to Fig. 6,

A =the moment of inertia of the spinning mass 10 with respect to the center of the universal joint 52.

C =the moment of inertia of the spinning mass 15 with respect to its own axis of rotation, which, in a balanced condition, is the axis of its own spindle shaft 21.

ω =the spinning speed of the spinner basket in radians per second.

Ω =the speed of gyration of the basket in radians per second either natural, or forced by the 20 gyrating shaft.

α =the angle of inclination of the spinner shaft 21 from true vertical when spinner basket is perfectly balanced about its own axis.

m =the spinning mass including the mass of the 25 basket and contents.

g =acceleration due to gravity.

h =the distance from the center of the universal joint 52 to the center of mass of the spinning mass, or radius of gyration.

A then equals mh^2 ; and C equals mr^2 where

r =the radius of gyration of a ring shaped flywheel having equivalent performance of the spinning mass.

It will be noted that the above Equation #1 is a 35 quadratic equation. Solving the equation,

$$(2) \quad \Omega = \frac{+C\omega \pm \sqrt{C^2\omega^2 - 4A \cos \alpha mgh}}{2A \cos \alpha}$$

The quantities in the above equations, A , C , m , 40 g and h , are fixed for any installation with the basket carrying any given load. Assuming that the spin speed is also fixed, and the angle with the vertical is also fixed, Equation #2 has two 45 solutions for the gyrating speed, one of which may be called the "lower critical gyration speed" and the other of which may be called the "upper critical gyration speed."

At these critical speeds of gyration, the basket axis will precess about its universal joint and at the given angle with vertical, the system will be 50 in complete equilibrium, the angle α neither increasing nor decreasing. If, however, the gyrating speed be increased above its lower critical speed, the condition of equilibrium is changed and the restoring force tending to place the basket axis in true vertical position moves the basket axis toward true vertical position. On the other hand, if the gyrating speed be decreased below its lower critical speed, the basket axis will 55 depart further away from true vertical position. At the upper critical speed of gyration, I have found a contrary behavior. Here, increasing the gyrating speed above the upper critical speed causes the basket axis to move further away 60 from vertical, while decreasing the gyrating speed below the upper critical speed causes the basket axis to move toward vertical.

I have found that at any speed of gyration in the zone between the upper and lower critical 70 speeds, a preponderant restoring force is generated which causes a movement of the basket axis always toward true vertical position. Furthermore, I have found that all speeds suitable for the washing operation fall within this zone, 75

lying between the upper and lower critical speeds.

It will be understood that the above invention may be applied to any size machine, either for household purposes or for commercial laundry purposes and that the various dimensions and capacities of the basket and the proper speeds of the spin and gyrating shafts will occur to those skilled in the art from the above description.

However, for purposes of disclosure, a specific example is given. The spinner basket may be approximately eighteen inches in diameter. The weight of the spinning mass including basket and clothes and water remaining in the clothes when maximum spinning speed is reached, may be approximately forty pounds. During the washing operation the total weight will be nearer seventy-five pounds as there will be about six gallons of water, plus the clothes and spinner basket weight. The distance between the center of universal joint 52 and the center of mass of the basket and contents may run about eighteen inches. The spinning speed of spin shaft 12 may run about 1200 R. P. M. and the gyrating speed of gyrating shaft 13 may run about 120 R. P. M.

Thus, it will be seen that a combined washing and drying machine is provided that is simple in construction and operation. Both spin and gyrating shafts are located below the basket 30 to permit easy access to the top of the basket. Since the basket spills no water during washing, a minimum amount of water is consumed. A suitable water level in the basket for washing will be about even with the holes 26.

This type of machine also lends itself admirably for full automatic operation, as both washing and drying operations may be carried on with the clothes in the same container. No water circulation is required since water is prevented from sloshing out of the basket during washing and the tank 10 may be made of minimum capacity since it does not have to store water. The pump 16 runs only during the drying operation when water is being expelled from the basket. The guard ring 25 effectively prevents the discharge of clothes during washing and drying and the large number of holes 26 permit the water to be expelled during drying.

The washing action is achieved by the gyrating shaft rotating at the same speed as is used for correction purposes during the drying operation. A positive gyrating drive is achieved for the washing operation.

The machine may be almost completely made 55 of pressed metal parts and impregnated oilless bearings may be used. Due to the absence of toothed gears, the machine will be noiseless in operation and due to the perfect gyro-balancing obtained, the tank and frame will stand at substantially complete rest when the machine is either spinning or washing.

The frictional engagement between cup 61 and rings 60 is established by the weight of the spinner basket, clothes and water, and suitable guards are provided for preventing water from getting into the bearings and for preventing grease from getting onto the friction surfaces.

The two-part cover for the tank is convenient, as it is only necessary to remove the center lid 38 for inserting clothers into the basket and removing them from the basket. The ring 37 normally stays in place and acts as a guard to prevent water discharged from the basket 11 during drying from splattering out of the tank 10. The guard ring 37 is completely removable from

the tank for cleaning purposes and to permit the spinner basket to be removed. This member may be easily lifted out of the machine, the splined basket shaft 21 lifting out the sleeve shaft 56 and being easily replaceable therein.

It will be understood that the above theory of operation is given for the sole purpose of assisting in an understanding of the invention and is not given in any limiting sense. So far as known at the present time, this theory is correct, but it will be understood that, regardless of theory, the machine will operate in the manner described if built according to the teachings of the invention.

Reference is made to my co-pending divisional application, Serial No. 329,069, filed April 11, 1940, which contains claims to certain features of the tank and of the basket.

Reference is also made to my co-pending divisional application, Serial No. 379,238, filed February 17, 1941, which contains claims to the mechanism for shifting between washing and drying positions and to the electrical contact mechanism for controlling the sequence of operations.

While certain novel features of the invention have been disclosed and are pointed out in the annexed claims, it will be understood that various omissions, substitutions and changes may be made by those skilled in the art without departing from the spirit of the invention.

What is claimed is:

1. In a centrifugal machine, a rotatable basket, a stationary support under said basket, a drive shaft having an upper section connected to said basket and a lower section rotatably mounted upon said support, a universal connection between said sections, means for driving said lower section at centrifugally discharging speed, a hollow gyrating shaft surrounding said first drive shaft and spaced therefrom to permit said upper section to precess, a spherical frictional member journaled on said upper section, said hollow gyrating shaft having a member having frictional engagement with said spherical member.

2. In a laundry machine, a shaft assembly comprising a supporting sleeve, a hollow shaft rotatably mounted within said sleeve, a shaft rotatably mounted within said hollow shaft and having a lower section and an upper section with a universal joint therebetween, a basket, a detachable connection between said upper section and said basket, and cooperating elements on said hollow shaft and on said upper section, whereby to impart a gyrating motion to said basket.

3. In a laundry machine, a shaft assembly comprising a supporting sleeve, a hollow shaft within said sleeve, spaced upper and lower radial bearings between said sleeve and hollow shaft, an axial thrust bearing between said sleeve and said hollow shaft, a shaft within said hollow shaft having a lower section and an upper section with a universal joint therebetween, axial and radial bearings between said lower section and said hollow shaft, said upper section ending in a coupling element, a basket having a stub shaft with a coupling element detachably engaging said first coupling element, a spherical member journaled on said upper section, a spherical member secured to said hollow shaft engaging said first spherical member.

4. In a laundry machine, a shaft assembly comprising a supporting sleeve, a hollow shaft within said sleeve, spaced upper and lower radial bearings between said sleeve and hollow shaft,

said lower bearing also including a thrust bearing with said hollow shaft, a shaft within said hollow shaft and having a lower section and an upper section with a universal joint therebetween, 5 an axial and radial bearing between said lower section and said hollow shaft, said upper section ending in a splined sleeve, a basket having a splined stub shaft fitting within said splined sleeve, a spherical cup member journaled on 10 said splined sleeve, a spherical ring secured to said hollow shaft frictionally engaging said cup member, a ring having an off-center recess secured to said hollow shaft, a second ring journaled on said splined sleeve and selectively engageable in said recess.

5. In a washing and drying machine, a clothes basket, a drive shaft having an upper section secured to said basket and having a lower section journaled to rotate about a vertical axis with a universal joint therebetween, a hollow gyrating shaft surrounding said drive shaft and spaced from said upper section, permitting said upper section to execute conical movement, a spherical frictional member journaled on said upper section, said gyrating shaft having a spherical surface secured thereto and adapted to engage said spherical member during the drying operation, said gyrating shaft having an off-center abutment, and a hub member journaled on said upper section adapted to engage said abutment for washing.

6. In a washing and drying machine, a basket, a drive shaft having an upper section secured to said basket and having a lower section journaled to rotate about a vertical axis with a universal joint therebetween, a hollow gyrating shaft surrounding said drive shaft, permitting said upper section to execute conical movement, a spherical frictional member journaled on said upper section, a spherical ring secured to said gyrating shaft and adapted to engage said spherical member during the drying operation, a gyrating ring having an off-center recess, and a hub member journaled on said upper section adapted to engage in said recess for washing.

7. In a laundry machine, a supporting structure including a tank, drive shafts passing through the bottom of said tank including an inner spin shaft and an outer gyrating shaft, a large horizontally disposed bevel gear on said gyrating shaft, a smaller bevel gear on said spin shaft, an electric motor having its main drive shaft arranged at an angle between horizontal and vertical and having a larger bevel gear on its lower end engaging said spin shaft bevel gear, 55 and a smaller bevel gear on its upper end engaging said gyrating shaft bevel gear, a hanger pivotally suspended from said supporting structure, a saddle pivotally mounted on said hanger, said motor being mounted on said saddle, and spring means operating between said motor and supporting structure to yieldably hold said motor gears in engagement with said shaft gears.

8. In a laundry machine, a tank, laundry devices located in the tank, first and second drive shafts for operating said laundry devices, gears on said shafts, an electric motor having gears on opposite ends directly engaging said drive shaft gears, and means for yieldably holding said gears in engagement.

9. In a laundry machine, a supporting structure including a tank, operating drive shafts passing through the bottom of said tank and including an inner shaft and an outer shaft, a larger bevel gear on one of said shafts, a smaller bevel gear on said other shaft, a motor assembly

comprising an electric motor having its main drive shaft arranged at an angle between horizontal and vertical, said motor drive shaft having bevel gears on opposite ends engaging said operating drive shaft bevel gears, a support pivotally mounted on said supporting structure, means pivotally mounting said motor on said support, and spring means operating between said motor assembly and supporting structure to yieldably hold said motor gears in engagement with said operating shaft gears.

10. In a laundry machine, laundry apparatus comprising a clothes basket, driving means for said basket including an outer hollow gyrating shaft and an inner spin shaft, said spin shaft comprising telescoping elements, the lower of which is axially movable, bevel gears on said gyrating and spin shafts, an electric motor having bevel gears on opposite ends, one of which engages said gyrating bevel gear continuously and the other of which engages said spin shaft bevel gear only during drying, a brake ring under said spin shaft bevel gear having two positions, the lower position releasing said spin shaft bevel gear and permitting it to engage its motor drive gear for drying, the upper position raising said spin shaft bevel gear and said lower element and holding them stationary for washing.

11. In a washing and drying machine, a rotatable basket assembly, a stationary support under said basket assembly, a spin shaft rotatably mounted upon said support, a universal connection between said spin shaft and said basket assembly, a hollow shaft surrounding said spin shaft, connections between said hollow shaft and said basket assembly for applying a corrective force thereto during extraction, means for driving both said shafts for the extracting operation, and means for arresting movement of said spin shaft but continuing movement of said hollow shaft for the washing operation.

12. In a laundry machine, a basket assembly including a basket closed at one end of its axis and open at its other end for insertion and removal of articles, a plurality of driving members engaging said basket assembly adjacent said closed end, means for imparting spinning speed to said basket through one of said members for drying, means for imparting a translatory movement to the axis of said basket through the other of said members for washing.

13. A washing machine comprising a container for holding the clothes to be washed, an upright shaft to support said container with its axis substantially vertical, a universal mounting for said shaft, means to effect centrifugal extraction of the washing fluid from the clothes, means operatively connected to said shaft to gyrate the same in an orbital path to effect washing, control mechanism for said two means effecting a continued operation of said second-named means, at least during the initial operation of said first-named means, whereby said second-named means decreases the magnitude of the gyration of said shaft during the acceleration thereof by said first-named means.

14. In a combined washer and extractor, a basket adapted to contain clothes and washing fluid, a member secured at its upper end to the central portion of said basket and secured at its lower end by means of a universal joint to a vertical shaft, a power unit, drive means connecting said power unit and shaft to rotate the basket at high speed to effect extraction, a sleeve surrounding said member, means carried by said

5 sleeve adapted to engage said member to tilt said member and basket about said universal joint to effect washing and a second drive means connecting said power unit and sleeve to rotate the same.

15. In a combined washer and extractor, a basket to contain clothes and washing fluid, a support including a fixed vertical bearing tube, a low speed driving sleeve mounted in said tube, a high speed driving shaft within said sleeve, a member secured to said basket at its upper end and connected through a universal joint to said shaft at its lower end, means operatively connected to said sleeve and member to tilt said

10 member about said joint upon sleeve rotation to effect washing, means to restrain rotation of said shaft during washing and means to rotate said shaft at high speed to extract the washing fluid from the clothes.

16. In a combined washer and extractor, a basket adapted to contain clothes and washing fluid, a supporting structure comprising a vertically extending tube, a low speed driving sleeve rotatably mounted in said tube, a high speed

25 driving shaft rotatably mounted in said sleeve, a member depending downwardly from the central portion of said basket, a universal joint connecting said member and shaft to mount said member for tilting about said universal joint

30 during washing and extracting, means operatively connecting said sleeve and member to progressively tilt said member about said joint in response to sleeve rotation to effect washing, means to restrain the rotation of said shaft during

35 washing and means to release said restraining means and rotate said shaft at a high speed to effect extraction, the release of said restraining means and the high speed rotation of said shaft being effective to interrupt the connection 40 provided by said first-named means.

17. In a combined washing and drying machine, a shaft assembly comprising an outer supporting sleeve, a hollow shaft rotatably mounted within said sleeve, an inner shaft rotatably mounted within said hollow shaft and having a lower section and an upper section with a universal joint therebetween, said sleeve and hollow shaft permitting conical movement of said upper

50 section, a basket assembly secured to said upper section, cooperating elements between said shafts and said basket assembly, means for driving said inner shaft to rotate said basket at centrifugally drying speed, means for driving said hollow shaft to impart a slow speed motion to said basket.

18. In a centrifugal machine, a basket rotatable about a vertical axis, means for supporting said basket below its center of mass including concentric inner and outer shafts, said inner shaft

60 having a universal joint to permit lateral movement of its axis with respect to the axis of the outer shaft, connecting devices between said shafts and said basket, means for driving said inner shaft for centrifugal extraction, and means 65 for driving said outer shaft to control the translational movement of the basket axis.

19. In a centrifugal machine, an open top basket, means for supporting said basket for rotation about a vertical axis and to permit precession about a point under the center of mass of the basket, a plurality of driving devices applied to the underside of said basket, one of said driving devices spinning said basket substantially about its own axis, the other of said driving devices imparting a circular movement to said

basket axis about a true vertical line whenever the basket axis departs from true vertical.

20. In a laundry machine, an open top basket rotatable upon a vertical axis, concentric inner and outer shafts under said basket and having driving relation therewith, a universal joint incorporated in said inner shaft to permit it to partake of a movement transverse to the axis of said outer shaft, means for driving said inner shaft for centrifugal extraction, means to drive said outer shaft for washing.

21. In a laundry machine, a supporting structure including a tank, laundry devices in said tank, operating drive shafts passing through the bottom of said tank including an inner shaft and an outer shaft for operating said laundry devices, a horizontally disposed bevel friction gear on said outer shaft, a second horizontally disposed bevel friction gear on said inner shaft, an electric motor having its main drive shaft arranged at an angle between horizontal and vertical, said motor drive shaft having a bevel friction gear on its lower end adapted to engage said inner shaft bevel gear and a second bevel friction gear on its upper end adapted to engage said outer shaft bevel gear, and means holding said motor shaft gears in engagement with their respective operating drive shaft gears.

22. In a laundry machine, a supporting structure including a tank, laundry devices in said tank, operating drive shafts passing through the bottom of said tank including an inner shaft and an outer shaft for operating said laundry

devices, a large horizontally disposed friction bevel gear on said outer shaft, a second horizontally disposed friction bevel gear on said inner shaft, an electric motor having its main drive shaft arranged at an angle between horizontal and vertical, said motor drive shaft having a friction bevel gear on its lower end adapted to engage said inner shaft gear and a second friction bevel gear on its upper end adapted to engage said outer shaft gear, means yieldably holding both said motor gears in engagement with their respective operating shaft gears for one laundry operation, and means disengaging said lower motor shaft gear and its respective operating shaft gear while maintaining engagement of said upper motor shaft gear and its respective drive shaft gear for the other laundry operation.

23. In a laundry machine, a supporting structure including a tank, laundry devices in said tank, first and second operating shafts for driving said laundry devices, friction gears respectively on said shafts, an electric motor having friction gears on the opposite ends of its drive shaft adapted directly to engage said operating shaft gears, means supporting said motor on said structure to permit angular bodily movement of the motor with respect to said operating shafts, means for selectively separating and engaging a set of said operating shaft and motor shaft gears to control the movement of the laundry devices driven thereby.

JAY GRANT DE REMER.
